CLAIM

The ornamental design for a storage container, as show and described.

DESCRIPTION

FIG. 1 is a top perspective view of a first embodiment of a storage container;

FIG. 2 is a front elevation view of the storage container of FIG. 1;

FIG. 3 is a rear elevation view of the storage container of FIG. 1, shown with attached backing plates;

FIG. 4 is another rear elevation view of the storage container of FIG. 1, with the backing plates shown removed;

FIG. 5 is a top plan view of the storage container of FIG. 1;

FIG. 6 is a bottom plan view of the storage container of FIG. 1;

FIG. 7 is a side elevation view of the storage container of FIG. 1, the opposite elevation side view being a mirror image thereof;

FIG. 8 is a bottom perspective view of the storage container of FIG. 1;

FIG. 9 is a top perspective view of a second embodiment of a storage container;

FIG. 10 is a front elevation view of the storage container of FIG. 9;

FIG. 11 is a rear elevation view of the storage container of FIG. 9, shown attached backing plates;

FIG. 12 is another rear elevation view of the storage container of FIG. 9 with the backing plates shown removed;

FIG. 13 is a top plan view of the storage container of FIG. 9;

FIG. 14 is a bottom plan view of the storage container of FIG. 9;

FIG. 15 is a side elevation view of the storage container of FIG. 9, the opposite elevation side view being a mirror image thereof; and,

FIG. 16 is a bottom perspective view of the storage container of FIG. 9.

(Continued)

The broken lines shown in the FIG. 3 and FIG. 11 are included for the environmental purpose of illustrating backing plates on the storage container only and form no part of the claimed design.
